United States Patent Office

Des. 223,427
Patented Apr. 11, 1972

223,427

DUAL PURPOSE VEHICLE TIRE

Eugene Bordinat, Jr., Birmingham, Mich., assignor to
Ford Motor Company, Dearborn, Mich.

Filed Dec. 4, 1970, Ser. No. 26,294

Term of patent 14 years

Int. Cl. D12—15

U.S. Cl. D90—20

FIG. 1

FIG.3

FIG.2

FIG.4

FIG. 1 is a perspective view of my novel design for a dual purpose tire.

FIG. 2 is a side elevational view of the tire of FIG. 1,

FIG. 3 is a cross sectional view of the tire of FIG. 1, and

FIG. 4 is a plan view of a portion of the tread of the tire of FIG. 1.

I claim:

The ornamental design for a dual purpose vehicle tire, substantially as shown and described.
